(57) **CLAIM**

The ornamental design for an outlet, as shown and described.

DESCRIPTION

FIG. 1 is a front perspective view of an outlet.

FIG. 2 is a rear perspective view thereof.

FIG. 3 is a front elevation view thereof.

FIG. 4 is a rear elevation view thereof.

FIG. 5 is a right side elevation view thereof. A left side elevation view is a mirror image of the right side elevation view.

FIG. 6 is a top plan view thereof.

FIG. 7 is a bottom plan view thereof.

FIG. 8 is a cross-sectional view taken along the line 8-8 in FIG. 3; and,

FIG. 9 is a cross-sectional view taken along the line 9-9 in FIG. 5.

The broken lines shown in the drawings illustrate portions of the outlet that form no part of the claimed design.
